Samuel West Design for Church Window

DESIGNS 4492

PATENTED Nov 22 1870

Witnesses,
S. M. Stearns.
W. F. Cambridge

Inventor,
Samuel West

United States Patent Office.

SAMUEL WEST, OF BOSTON, MASSACHUSETTS.

Design No. 4,492, dated November 22, 1870.

DESIGN FOR CHURCH-WINDOW GLASS.

The Schedule referred to in these Letters Patent and making part of the same.

To all whom it may concern:

Be it known that I, SAMUEL WEST, of Boston, in the county of Suffolk and State of Massachusetts, have invented a Design for the Glass of Church-Windows, of which the following is a full, clear, and exact description, reference being had to the accompanying photograph, forming part of this specification.

My invention consists in producing on church-window glass a new design, commonly known by ornamentalists of glass as "*la Greque*" pattern.

To enable others skilled in the art of cutting and ornamenting glass to understand my invention, I will proceed to describe the same.

In the said photograph is represented one-half of the design, first originated and applied by me to a church-window, the other half of the design being an exact symmetrical counterpart of the configuration shown.

A stencil-plate, bearing the form of the design, is placed on the glass covered with a coating of enamel, and a *fac simile* is thus produced thereon.

The characteristic feature in the "*la Greque*" style

of pattern is the combination of straight and curved lines in such manner as to present many angular points, the intersection of the majority of the straight lines with the curved lines being other than tangential in contradistinction to "*L'Arabesque*" style, in which the distinguishing feature is a series of straight and curved lines tangential to each other, and in which a greater freedom is given to the curves than in the "*la Greque*" pattern.

Claim.

What I claim as my invention, and desire to secure by Letters Patent, is—

The design for the glass of a church-window, substantially as shown and described.

Witness my hand this 4th day of November, A. D. 1870.

SAMUEL WEST.
